UNITED STATES PATENT OFFICE.

ADAM C. WILLIAMS, OF RAVENNA, OHIO.

DESIGN FOR A RAISIN-SEEDER FRAME.

SPECIFICATION forming part of Design No. 25,869, dated August 4, 1896.

Application filed May 15, 1896. Serial No. 591,725. Term of patent 14 years.

To all whom it may concern:

Be it known that I, ADAM C. WILLIAMS, of Ravenna, Portage county, Ohio, have invented and produced a certain new and useful Design 5 for Raisin-Seeder Frames; and I do hereby declare the following to be a full, clear, and exact description of the invention, such as will enable others skilled in the art to which it pertains to make and use the same.

My design relates to raisin-seeder frames; and it consists in the following features, as will be hereinafter fully set forth.

In the drawing the figure is a view in perspective of a frame constructed according to 15 my design.

The leading features of the design are, first, the angular form of the neck with bifurcated foot; second, in the ornamental configuration of the brace-piece extending from the upper 20 branch of the bifurcated foot to the lower portion of the horizontal arm of the angular neck; third, in the head having a side plate and back curved on the inside and angular on the exterior with a boss surmounting the horizontal ledge of the back on the outside and a hopper-shaped portion surmounting the whole.

The angular neck is composed of vertical arm A and horizontal arm A', the vertical 25 arm being provided, at its lower end, with a bifurcated foot, having lower horizontal projections a and upper horizontal projection a'.

Extending from the top of the projection a' and between it and the under side of the horizontal arm A' of the neck is a brace B of open-work, formed by a series of ogee curves bbbb, crossing each other, and thus in turn forming a series of elliptical openings b' b' b', in the interior of which are located disks b²b³b². On the exterior, where the ogee curves cross, 35 40 are located at either side segments b³b³, the whole constituting the brace, as shown and described.

The head C of the frame is constructed with side plate c and back piece c', curved on the 45 interior and on the exterior formed with vertical flat face c² and horizontal flat face c³, the horizontal face being surmounted by a boss d, and the whole surmounted by a hopper-shaped portion D. This head portion is 50 secured to the horizontal arm A' of the neck at the vertical face c².

What I claim is—

The design for a raisin-seeder frame as herein described and shown in the accompanying 55 drawing.

In testimony whereof I sign this specification, in the presence of two witnesses, this 30th day of April, 1896.

ADAM C. WILLIAMS.
